UNITED STATES PATENT OFFICE.

CHARLES A. HOFFMAN, OF MINNEAPOLIS, MINNESOTA.

EYEGLASS-MOUNTING.

No. 820,492.

Specification of Letters Patent.

Patented May 15, 1906.

Application filed November 14, 1904. Serial No. 232,576.

To all whom it may concern:

Be it known that I, CHARLES A. HOFFMAN, of Minneapolis, Hennepin county, Minnesota, have invented certain new and useful Improvements in Eyeglass-Mountings, of which the following is a specification.

This invention relates to mountings designed particularly for eyeglasses; and the object of the invention is to dispense with all screw, pin, and rivet holes, which weaken the parts usually at the point of greatest strain, and to avoid all soldering and brazing, which through the action of the heat has a tendency to destroy the stiffness and elasticity of the spring, and render it less suitable for the purpose designed.

A further object is to provide a mounting of simple construction, having but few parts which can be easily and quickly assembled.

The invention consists generally in a combined bridge or spring and nose-guard formed from a single piece of metal.

Further, the invention consists in providing a combined bridge and nose-guard that is adjustably mounted on the lens.

Further, the invention consists in various constructions and combinations, all as hereinafter described, and particularly pointed out in the claims.

In the accompanying drawings, forming part of this specification, Figure 1 is a rear view of an enlarged eyeglass-mounting embodying my invention. Fig. 2 is a top view of the same. Fig. 3 is a plan view of the bridge and nose-guard before being bent into proper shape for the mounting. Fig. 4 is a sectional view of a lens looking toward the end of the bridge. Fig. 5 is a detail sectional view showing the manner of securing the bridge and nose-guard to the lens. Fig. 6 is a detail of the clamp device that forms the connection between the lens and bridge.

In the drawings, 2 represents the lens, each of which is provided with a clamp consisting, preferably, of sheet-metal plates 3, adapted to be folded over one upon the other and adjustably secured together at one end by screws 4, fitting threaded holes 5 in the plates. Straps 6, having holes 7, are bent around the edges of the lens and are secured thereto by rivets 8. Depressions 9 are provided in the plates 3 upon each side of the strap 6 to receive points or teats 10 in the surface of the other straps, which act as guides for the one-piece bridge and nose-guards, as hereinafter described. The bridge or spring 11 and the

nose-guards 12 are stamped out of one piece, preferably sheet metal, and bent into the desired shape to form the mounting. The parts 13 of the bridge between its curved middle portion and the guards are adapted to fit in between the straps 3 and be clamped thereby when the screws 4 are tightened, the points 9 preventing vertical movement, but allowing the bridge and guard to be slipped horizontally back and forth toward or from the plane of the lens to fit the mounting to the contour of the nose. This form of clamp dispenses with screws or rivets, which are liable to wear and work loose, and avoids all necessity of brazing or soldering any of the parts. Between the nose-guards and the parts 13 finger-pieces 14 are provided that are bent inwardly, as shown in Fig. 2, to enable the wearer of the glasses to easily place them on the nose or remove them.

The plate from which the bridge or spring and guards are made can be bent into various shapes to fit the nose of the person for whom the mounting is made and to suit the taste of the optician or customer and cause the lens to hang in a normal position, or lower for reading purposes, or higher for distance vision, or, in fact, any position that best suits the needs or wishes of the purchaser.

The bridge and guards are not perforated at any point, and thus weakening of the mounting at such places that are subject to the greatest strain is avoided.

The clamp may be stamped out of sheet metal, as shown, or may be made in several pieces, if preferred. All brazing and soldering of the bridge and guard being avoided, the inherent stiffness and elasticity of the metal comprising the bridge and guard are retained.

I claim as my invention—

1. In an eyeglass-mounting, a bridge and nose-guards formed from a single piece of metal, the middle portion of which is curved to form the bridge and provided with forwardly-extending end loops, the ends of said loops being inwardly turned and extended rearwardly substantially parallel with one another to form the guards and finger-pieces projecting forwardly from said ends, substantially as described.

2. In an eyeglass-mounting, a bridge and nose-guards formed from a single piece of metal, the middle portion of which is curved to form the bridge and provided with forwardly-extending end loops, the ends of said

loops being inwardly turned and extended rearwardly and straddling the bridge to form the nose-guards, finger-pieces projecting forwardly from said ends and lens-clamps wherein in the said loops are slidably secured to permit the horizontal adjustment of the bridge and guards with respect to the vertical plane of the lens.

3. In an eyeglass-mounting, a bridge and 10 nose-guards formed from a single piece of metal, the middle portion of which is curved to form the bridge, and the ends are inwardly turned and extended rearwardly substantially parallel with one another to form the guards, 15 and finger-pieces projecting forwardly from said ends, substantially as described.

4. In an eyeglass-mounting, the combination, with a bridge and nose-guards formed in one piece, the middle portion of which is 20 bowed or curved to form the bridge and the ends inwardly turned and rearwardly extended to form the guards, and clamps secured to the lens and wherein the bridge and guards are slidably supported to permit their horizontal adjustment with respect to the vertical plane of the lens.

5. In an eyeglass-mounting, a lens-clamp comprising a plate having one end folded over upon the other and adjustably secured thereto, a space being provided between said ends wherein the bridge is clamped, and straps provided on opposite sides of said plate and adapted to be bent toward each other to straddle the lens and be secured thereto, substantially as described.

6. In an eyeglass-mounting, a lens-clamp comprising a plate having its ends folded together with a space between them, a series of teats or points being formed on one end of the plate to enter depressions in the other end and form guides for the bridge, means for drawing the ends of said plate together to clamp the bridge, and straps provided on said plate and adapted to straddle the lens and be secured thereto, substantially as de- 45

In witness whereof I have hereunto set my hand this 7th day of November, 1904.

CHARLES A. HOFFMAN.
